FLY ASH REMOVAL SYSTEM

Ernest C. Webb, Cleveland, Ohio

Application July 28, 1943, Serial No. 496,437

6 Claims. (Cl. 110—165)

The main object of this invention is to collect the fly ash from behind the bridge wall of a boiler and return it to the combustion chamber thereof in order that all of the combustibles therein may be burned and the heat extracted therefrom.

The second object is to construct a system of the class described which will be relatively inexpensive to construct and which is at the same time highly efficient.

These and other objects are accomplished in the manner set forth in the following specification, as illustrated in the accompanying drawings, in which:

Fig. 1 is a horizontal section taken along the line 1—1 in Fig. 2.

Fig. 2 is a vertical section taken along the line 2—2 in Fig. 1.

Fig. 3 is a vertical section taken along the line 3—3 in Fig. 2.

Fig. 4 is a fragmentary front elevation of a boiler front showing a representative installation and cutting through the pneumatic coal feeder along the line 4—4 in Fig. 2.

Similar numerals refer to similar parts throughout the several views.

Referring in detail to the drawings there is shown a boiler front 10 having the inspection openings 11, ash pit openings 12 and the opening 13 through which is inserted the nozzle 14 of the pneumatic conveyor pipe 15, provided with elbows 16. The tip 17 of the nozzle 14 is preferably made adjustable to assist in controlling the spreading action of the fuel. The usual grates 18 are also indicated.

At the back of the grates 18 is disposed the bridge wall 19 whose rear side 20 slopes downwardly to the ash collection pit 21 whose sides 22 are preferably vertical. The side 23 slopes upwardly from the pit 21 to the rear wall 24 of the setting. Communication is gained to the pit 21 through the tunnel 25 which opens outwardly through the side wall 26. Across the pit 21 is placed a perforated grating 27 which extends preferably along the entire length of the tunnel 25 to the door 28 which forms a closure for the tunnel 25. The portion of the grating 27 which occupies the tunnel 25 is not perforated.

Below the grating 27 is placed a nozzle 29 of an ash ejector which operates on the Venturi principle. The Venturi tube 30 is connected to the discharge pipe 31 which passes through the elbow 32 at the lower front corner of the furnace, and then upwardly through the elbow 33 and thence discharges through the pipe 34 to the combustion space of the furnace. The location

of the pipe 34 will depend largely upon the requirements of a particular installation, and is herein shown only by way of illustration.

The nozzle 29 is connected by the pipe 35 to the manifold air box 36 to the upper end of which is connected the pipes 37 which in this case occupy a horizontal plane above the pit 21 and tunnel 25 from whence they extend through the side wall 26 into the manifold box 38 which is connected to the pressure fan 39 operated by the motor 40.

It is desirable to provide a refractory shield 41 over the pipes 37 and to slope the sides 42 to prevent the accumulation of fly ash thereon.

15 The end walls 43 and 44 also slope toward the center of the space behind the bridge wall 19 so that fly ash settling behind the bridge wall 19 will settle on the surfaces 20, 23, 42, 43 or 44. The slope of the surfaces is such as to discourage thick accumulations of fly ash and to encourage it being deposited on the grate 27 within the pit 21.

It is obvious that the air-cooled shield reduces the temperature of the ash or combination of ash 25 and combustible material entering the conveyor. Also that this shield reduces the temperature of the perforated grating below the temperature it would obtain if it were exposed directly to the furnace temperature unprotected by this air cooled shield.

30 It will be noted that the elbows 32 and 33 are provided with covers 45 which are preferably removable to make it possible to take care of any congestion of ash within the pipe itself, although ordinarily such action is not necessary.

35 Since some of the materials will not pass through the openings in the grate 27, they are simply raked out over the plate 27 through the door 28 and removed therefrom.

40 An outstanding advantage arises from the reduction of the fly ash temperature below the fusing point, thereby permitting it to be drawn off pneumatically instead of forming clinkers which must be otherwise handled as is commonly the case.

I claim:

1. A fly ash removal system having in combination a furnace including primary and secondary combustion chambers, a fly ash collecting pit disposed below said secondary combustion chamber and means for shielding said pit from the radiant heat of said secondary combustion chamber for the purpose of preventing the fusing of fly ash deposited within said pit.

55 2. A fly ash removal system having in com-

bination a furnace including a primary combustion chamber in which fresh fuel is burned, a secondary combustion chamber in which gases released in said primary chamber as well as solid fuel carried by said gases are consumed, a fly ash collection pit under said secondary chamber, means for shielding fly ash against radiant heat after it enters the pit, and means for holding said ash below the fusing point while in said pit.

3. A fly ash removal system having in combination a furnace including primary and secondary combustion chambers, the former having a grate structure upon which fuel may be burned and the latter a combustion space in which gases released in said primary chamber, together with solids carried by said gases are burned in suspension, an ash collecting pit under said secondary chamber, means for shielding the fly ash produced in the secondary chamber from the radiant heat produced therein after said fly ash has settled, means for holding the temperature of said fly ash below the fusing point while in said pit and means for removing the ash from said pit in an unfused condition.

4. A fly ash removal system having in combination a furnace including primary and secondary combustion chambers separated by a bridge wall, the primary chamber in front of said wall having a grate structure upon which solids may be burned and above which powdered fuel may be burned in suspension, the secondary chamber behind said bridge wall being employed to burn gases released by said primary chamber and which have passed over said bridge wall without being consumed, together with particles of solid

fuel carried by said partially consumed gases, the bottom of said secondary chamber having sloping sides terminating in an ash collecting tunnel, a shield over said tunnel protecting the fly ash therein against direct radiant heat generated in said secondary chamber, means for dissipating heat from said tunnel for the purpose of holding the fly ash therein below the fusing point, and pneumatic means for conveying said cooled fly ash back to the primary combustion chamber.

5. A furnace having a primary combustion chamber a secondary combustion chamber separated from the primary chamber by means of a bridge wall, including a grating at the bottom of said secondary chamber, said secondary chamber having inclined refractory walls converging downwardly toward said grating, a plurality of horizontal cooling pipes disposed over said grating, an ash ejector having its intake below said grating and a fan for forcing air through said cooling pipes and through the ash ejector whereby the temperature of the ash on the grating and beneath said grating may be held below an ash fusing temperature.

6. In a furnace having primary and secondary combustion chambers, the combination of a grating disposed at the bottom of the secondary combustion chamber, a shield of air cooled pipes disposed over said grating, a pneumatic ash ejector disposed under said grating taking air from said cooling pipes and a fan for supplying air to said cooling pipes.

ERNEST C. WEBB.
